UNITED STATES PATENT OFFICE.

HARRY J. MOREY, OF SYRACUSE, NEW YORK, ASSIGNOR TO PASS & SEYMOUR, INC., OF SOLVAY, NEW YORK, A CORPORATION OF NEW YORK.

KEY-SOCKET.

1,262,969.

Specification of Letters Patent. Patented Apr. 16, 1918.

Application filed August 3, 1916. Serial No. 112,976.

To all whom it may concern:

Be it known that I, HARRY J. MOREY, a citizen of the United States, and resident of Syracuse, county of Onondaga, State of New York, have invented certain new and useful Improvements in Key-Sockets, of which the following is a specification.

This invention relates to electric appliances and more particularly to improvements in key sockets. The object is to 10 simplify the construction of key sockets and provide a structure in which the fixed and moving parts of the device are held on the single piece porcelain base in a novel 15 manner, which eliminates extra devices for holding the parts in place. The above and other objects and the novel feature of the invention will be apparent from the following description taken in connection with 20 the drawing in which,

Figures 1 and 2 are side views of a lamp socket embodying my invention, being taken at right angles to each other and the outside shell being omitted;

Fig. 3 is a top plan view of the same, the porcelain base being shown in dotted lines to illustrate the position occupied by the switch mechanism;

Fig. 4 is a bottom plan view of the same; 30 Fig. 5 is a vertical central section taken on the line 5—5 of Fig. 2, parts thereof being shown in elevation and an open position of the switch being shown in dotted lines; and

Figs. 6, 7 and 8 are views of details of the device.

The socket has a base 10 which consists of a single piece of porcelain or other suitable insulating material and is closed at 40 the top end. At the lower end the base has a cavity 11 therein in which the switch mechanism is located. The cavity in the base has two aligned circular recesses 12 and 13 which are located on opposite sides of a chamber 14. The recesses 12 and 13 constitute bearings for the operating spindle 15 which fits therein and which carries an insulating key 16 at its outer end. The spindle 15 is provided with two lugs 17 45 on opposite sides thereof which have a loose connection with a hollow oblong cam 18 in the well known manner. The cam member 18 is rotated when the spindle 15 is turned and operates in the chamber 14.

The lugs 17 lock the cam 18 on the spindle 55 15 and the cam prevents the withdrawal of the spindle since it will engage against the wall 141 of the chamber 14 when the spindle is pulled downwardly. There are two other chambers 19 and 20 on opposite sides 60 of the chamber 14 which open in opposite sides of the outer face of the base 10.

The base 10 has a disk 21 of insulating material, such as fiber secured over the lower side of the cavity. The fiber disk 21 carries 65 the usual center spring contact 22 on its outer side and on its inner side it carries a spring switch member 23. The center contact 22 and the switch member 23 are secured to the fiber disk 21 by a single hollow rivet 24 which engages one end of each of the springs. The center contact has a projection 221 at its fixed end which extends into an opening 211 in the disk 21 to keep the contact from turning. 75

The spring switch member 23 consists of a single strip of resilient, conducting material such as copper. The strip is doubled on itself to form an upright part 25 and a bent part 26, the latter abutting against the spindle 15 and against shoulders 27, adjacent the bearing recess 13, thereby holding the spindle in the bearing recesses 12 and 13. The free end of the switch member 23 extends centrally through the cavity and into 80 the chamber 19 where it is moved by the cam member 18 into engagement with the conducting plate 28. The resiliency of the bent switch member restores it to open position, indicated in dotted lines, when the spindle is turned a quarter turn in either direction. The cam allows the switch to work with a snap action, as is well known. The bottom of the chamber 19 forms a stop 85 for the spring switch. 90

The conducting plate 28 has a curved part 29 at one end fitting into and locked in a curved recess 30 in the bottom face of the base 10. The plate 28 extends across the chamber 19 into a recess 31 in the base 100 and on the opposite side of the chamber and at that end the plate is bent downwardly to form an integral terminal plate 32 disposed in the recess 33 and provided with a terminal securing screw 34. This 105 plate 28 is held in its recesses solely by the insulating disk 21.

The outer side of the disk 21 carries the

usual screw shell or lamp contact 35 which has inturned flanges 36 fitting against the disk 21 and engaged on the outer side by a U-shaped securing plate 37. The plate 37 is provided with a right angled lug 38 extending into the recess 39 in the base and provided with a terminal securing screw 40. The two arms of the plate 37 have holes which are threaded to receive the 10 threaded ends of the securing screws 41 which pass through the holes 42 in opposite sides of the base and are the only means for securing all of the parts together. The base 10 has wire-receiving grooves 43 in 15 line with the terminal screws 34 and 40.

Since the construction of the parts may be modified without departing from the spirit of the invention, I do not wish to be limited to the exact details illustrated.

20 What is claimed is:—

1. An electric switch mechanism comprising a base consisting of a block of insulating material having depressions therein and also having a cavity therein, an insulating 25 member secured to said base, a current conducting element fitting in the depressions in the base and held therein by said insulating member, a switch in said cavity, and means for operating said switch to cause it to engage said element.

2. An electric switch mechanism comprising a base consisting of a single block of insulating material having depressions therein, and also having a cavity therein and 35 bearing recesses in the bottom of said cavity, said cavity being closed at one end, an insulating disk closing the other end of said cavity, a current conducting plate fitting in said depressions and held therein by said 40 disk, said plate extending across the cavity, a switch mounted on the inner side of said disk and extending into said cavity, a switch spindle held in place in said bearing re-

cesses, and means operable by said spindle for causing the switch to engage said plate. 45

3. In an electric switch for key sockets, the combination of a base of insulating material having a cavity therein and a bearing for a spindle in said cavity, a spindle mounted in said bearing, a cam on said 50 spindle, and a switch in said cavity operable by said cam and having a part which extends across said bearing and holds the spindle in place therein.

4. In a key socket, the combination of a 55 base of insulating material having a cavity therein and bearing recesses in said cavity, a switch spindle rotatable in said bearing recesses, a cam on said spindle between said recesses, and a spring switch in said cavity, said switch being operable by said cam and having a part which extends across one of said bearing recesses to hold the spindle in place therein.

5. In a lamp socket, a base of insulating 65 material having a cavity therein bearing recesses for a switch spindle in the bottom of said cavity and depressions to receive and assist in retaining a current conducting plate on said base.

70 6. An electrical appliance comprising a base of insulating material having a recess in one of its faces, a switch spindle in said recess, a cam on said switch spindle, a switch contact plate bridging a part of the 75 recess in the base, an insulating plate closing the recess in the base and fitting against the outer side of said contact plate, and a switch in the recess having a part which holds the spindle in place, said switch being 80 operable by said cam to move it into engagement with said contact plate.

In testimony whereof I affix my signature.

HARRY J. MOREY.
